(57) **CLAIM**

The ornamental design for a drain strainer basket, as shown and described.

DESCRIPTION

FIG. 1 is an isometric top view of a drain strainer basket showing my new design.

FIG. 2 is an isometric bottom view thereof.

FIG. 3 is a front elevational view thereof.

FIG. 4 is a back elevational view thereof.

FIG. 5 is a left side elevational view thereof.

FIG. 6 is a right side elevational view thereof.

FIG. 7 is a top plan view thereof; and,

FIG. 8 is a bottom plan view thereof.

Shading shown in the figures is intended to represent the three-dimensional shape of the drain strainer basket, and is not intended to indicate surface decoration. The broken lines in the figures are for illustrative purposes only and form no part of the claimed design.
